CLAIM

The ornamental design for a gardening tool, as shown and described.

DESCRIPTION

FIG. 1 is a top plan view of a gardening tool, showing my new design;

FIG. 2 is a bottom plan view thereof;

FIG. 3 is a right side elevational view thereof, the left side being a mirror image thereof;

FIG. 4 is a frontal elevational view thereof;

FIG. 5 is a rearward elevational view thereof; and,

FIG. 6 is a perspective view taken from the top, front, and side elevational views thereof.

FIG. 1

FIG. 2

FIG. 4

FIG. 3

FIG. 6
